FIG. 1

FIG. 2

FIG. 3

INVENTOR.
FREDERICK C. HERSEE

BY *C. W. Fairbank*
ATTORNEY.

UNITED STATES PATENT OFFICE.

FREDERICK C. HERSEE, OF BOSTON, MASSACHUSETTS.

TIMER AND DISTRIBUTER.

1,203,560.

Specification of Letters Patent. Patented Oct. 31, 1916.

Application filed July 30, 1915. Serial No. 42,757.

to all whom it may concern:

Be it known that I, FREDERICK C. HERSEE, a citizen of the United States, and a resident of Boston, in the county of Suffolk and 5 State of Massachusetts, have invented certain new and useful Improvements in Timers and Distributers, of which the following is a specification.

This invention relates to certain improvements in timers and distributers and more particularly to that class in which a series of rigidly connected insulated contacts are supported in properly spaced positions about a coaxing rotatable contact member.

15 The main object of my invention is to produce a very simple and inexpensive construction adapted to better withstand and resist those influences working to reduce the life and efficiency of the constructions such 20 for instance as wear, strain, arcing and the like.

As important features of my improved construction, I mount metal contacts in a metal ring and insulated therefrom by comparatively narrow strips of insulating material so that the center rotatable contact is traveling forwardly all of the time on metal. This insures a substantially uniform wear rather than the irregular and uneven wear 30 resulting from mounting the metal contacts at spaced points and at a considerable distance apart in a ring of insulating material. Furthermore, the metal ring may be of the same kind and grade of material as the stationary contacts and as an important feature of my invention, is mounted in a casing of stamped or pressed material. Thus, the casing may be very cheaply formed and made of a less expensive material than the 35 ring carrying the contacts. For instance, the casing itself may be of pressed sheet metal, condensite, or any other pressed or stamped material.

As a further feature of my improved construction, I employ a spring normally under compression for pressing the movable contact outwardly toward the row of stationary contacts. By mounting it in the simple manner hereinafter described and combining 45 it with the other novel features to be described, movable contact is more effectively held in operative position, injury to the spring is prevented, and the length of life of the spring is increased.

Reference is to be had to the accompanying drawings in which I have illustrated one embodiment of my invention and in which similar reference characters indicate corresponding parts in the several views.

In these drawings, Figure 1 is an end view 55 showing the drive shaft in section; Fig. 2 is a transverse section in the plane of the contact members; and Fig. 3 is a central longitudinal section.

In the specific construction illustrated in 60 the accompanying drawings, I employ a casing 10 which may be of any suitable form or shape. The casing is made of pressed or stamped material and may be of either conducting or non-conducting material. For 65 instance, I may stamp or press it from sheet metal, condensite or other material. Within this casing of pressed material, I mount a metal ring 11 which may be secured in place in any suitable manner. Preferably, it is 70 held by the same means as holds the contact members as will be hereinafter described. In the inner surface of this metal ring 11, I provide a series of spaced pockets which 75 may be of any suitable form and within each 80 pocket I provide a contact member 12, the inner surface of which is curved and lies in the same arc as the inner surface of the ring. By making the pockets and contact members substantially crescent shaped, the 85 contact members may be forced into place and hold a curved plate 13 of insulating material in place and at the same time be self-centering. As shown, I connect to each contact member a screw 14 which may be riveted, 90 welded, soldered or keyed to the contact member so as to be rigid therewith and thus prevent it from rotating in respect thereto. For instance, I may drive a small pin 15 through the contact member into the 95 screw to properly connect them. The screw extends through a radial aperture in the ring and a registering aperture in the outside casing and is insulated from both by a series of washers 16, the outer one of which 100 engages with the outer surface of the casing and lies between a nut 17 and the outer sur-

face of the casing. Thus, by tightening the nut, the contact is firmly drawn into its pocket in the ring, the insulating plate and the insulating washers are held in place, and 5 the metal ring is rigidly secured to the casing of sheet material. The contact members are spaced at equal distances apart and their number may be varied in accordance with the use to which the device is to be put. I 10 have shown a device having four contact members adapted for use with a four-cylinder, four-cycle engine, but the number may be increased or decreased as desired.

A drive shaft 18 extends into the casing 15 substantially concentric with the ring 11 and carries a collar 19 substantially in the plane of the ring. This collar has a lug 20 on one side thereof and pivoted to the lug is an arm 21. The arm at one end carries a contact 20 member adapted to engage with the inner surface of the ring 11 and the series of contacts carried by the latter. The movable contact member may be in any suitable form, such for instance as a roller 22. The character 25 of this contact member forms no portion of my present invention. Between the roller and the pivotal support of the arm 21, I mount a spring 23, the opposite ends of which encircle studs 24 on the arm and 30 the collar. The spring is normally under compression so as to swing the contact member outwardly and this outward movement is limited by the engagement of the opposite end 25 of the arm which contacts with 35 the collar. The spring is thus protected between the arm and the collar, is comparatively short, and being a compression spring, capable of only a limited movement, does not readily lose its expansive force. In case it 40 does lose it, it may be very readily removed as its ends merely receive the studs which project toward each other and a new spring may be easily inserted.

In operation, the shaft with the movable 45 contact member is driven from the engine so that the movable contact member travels over the series of stationary members and closes the several circuits in succession as is well understood by those familiar with the 50 art. The insulation between the ring and the stationary contact being comparatively narrow, and substantially narrower than the roller constituting the movable contact, it is subjected to very little wear and thus the 55 movable contact member, even after the device becomes worn, may travel over a substantially smooth surface. In the drawings, I have not illustrated the complete casing, but only the parts involving my invention. 60 It is of course understood that there will be another casing section concentric with the shaft and coacting with the casing section shown, to prevent the access of dust, water,

and other foreign bodies to the contact members. It is of course understood that the 65 casing section shown is so mounted that it may have a limited rotative movement in order to advance or retard the time of circuit closing.

Having thus described my invention, 70 what I claim as new and desire to secure by Letters Patent is:

1. A timer including a casing of pressed material, a metal ring secured therein and provided with a series of pockets in its inner 75 surface, a series of metal contacts carried by said ring within said pockets, a layer of insulation within each pocket between the contact and said ring, said ring, contacts and insulation layers presenting a smooth cylindrical inner surface, and a contact member movable along said surface and adapted to engage with said first mentioned contacts in succession.

2. A timer including a series of spaced 85 metal parts arranged in succession and each presenting a curved inner surface, all of said surfaces lying in the same cylindrical plane, insulation separating each alternate metal part from all of the remaining metal parts, 90 a casing secured to and supporting the other alternate metal parts, and a contact member movable about the axis of said casing and resiliently pressed outwardly and movable along all of said metal surfaces. 95

3. A device of the character described, including a casing formed of pressed material, a metal ring disposed therein and having a series of pockets in the inner surface thereof, a series of contacts disposed 100 within said pockets and insulated from said ring and having their inner surfaces flush with the inner surface of said ring, terminals rigidly secured to said contact members and extending outward radially 105 through said ring and said casing and insulated from both, and means secured to said terminals outside of said casing for holding said casing, ring, contact members and terminals in rigid predetermined relationship. 110

4. In a device of the character described, a shaft, a collar secured thereto and having a lug integral therewith, an arm pivoted to said lug and having one end thereof carrying a brush and having the opposite end 115 adapted to engage with said collar to limit the movement of said arm in one direction, studs carried by said collar and said arm intermediate of said lug and said brush, and a comparatively short compression spring 120 having its opposite ends receiving said studs.

5. A timer including a shaft, a collar secured thereto and having a radially extending lug integral therewith, an arm pivoted intermediate of its ends to said lug and having one end carrying a brush and having the

opposite end adapted to engage with said Middlesex and State of Mass., this 28th day
collar to limit the movement of said arm in of July, A. D. 1915.
one direction, and a comparatively short
compression spring engaging with said col-
5 lar and with said arm at a point interme-
diate of the brush and said lug.
Signed at Waltham, in the county of

FREDERICK C. HERSEE.
